UNITED STATES PATENT OFFICE.

GLENN W. PACKER, OF CHICAGO, ILLINOIS, ASSIGNOR TO GOODMAN MANUFACTURING COMPANY, OF CHICAGO, ILLINOIS, A CORPORATION OF ILLINOIS.

SCRAPER.

Application filed May 19, 1921. Serial No. 470,771.

To all whom it may concern:

Be it known that I, GLENN W. PACKER, a citizen of the United States, residing at Chicago, in the county of Cook and State of Illinois, have invented a Scraper, of which the following is a specification.

This invention relates to improvements in scrapers used for transporting loose material, and more particularly to scrapers adapted to have reciprocating movement toward and away from the material to be transported.

The object of my invention is to provide an improved construction of a scraper of the class described, and to provide a novel method of operating the same.

With scrapers of the ordinary well known type having one open end, it is often found difficult to manipulate the scraper so as to be loaded easily, as for instance, when a pile of loose material is to be attacked, and the scraper is given reciprocating movement toward and away from the pile. Under these conditions a scraper of the ordinary type is loaded at the beginning of its forward movement, and the easiest method is usually first to move the scraper over or around the pile, and then "dig in" on the rear slope, preferably at the bottom, or "heel" of the pile if possible. Sometimes, however, the material is piled against a wall and in this case the scraper must be made to "dig in" on top or on the front slope of the pile. In either instance, the scraper must usually be manually guided into the pile, and scrapers are usually provided with handles for this purpose. Furthermore, the scraper is quite often loaded in excess of its capacity, and as it moves forwardly from the pile, the excess material drops off at the front edge, or "toe" of the pile and along the way, thereby requiring an excessive amount of power to load the scraper, and resulting in the elongation of the toe of the pile.

In the present invention, I propose to overcome these, and other objectional features of the ordinary scraper devices by providing a reciprocable scraper which digs into the forward edge or "toe" of the pile into position to be loaded during its rearward movement. My invention will be readily understood by reference to the drawings, which illustrate one form of scraper embody-

ing the features of novelty claimed in the appended claims.

In the drawings:

Figure 1 is a top plan view of a scraper constructed in accordance with my invention.

Figure 2 is a vertical cross-section of the scraper.

In this embodiment of my invention, the scraper is adapted to be moved by flexible draft ropes, comprising a head rope 10 and a tail rope 11, for moving the scraper forwardly and rearwardly, respectively. The apparatus is set up in the usual manner with the draft ropes trained over fixed guides or sheaves and operatively connected with any suitable power device, such as a hoisting engine.

The scraper comprises a body portion 12, having side walls 13, 13 connected by front and rear cross-members 14, and 15, respectively. The drawings illustrate a preferred form of scraper having no bottom, but a bottom may be found desirable under some circumstances, and may be provided without departing from the scope of my invention. The side walls 13, 13 diverge slightly toward the front end of the scraper, and the bottom margins of said walls are inclined or turned inwardly to form substantially horizontal cutting edges 16, 16, as shown.

The rear end of the scraper comprises two upright wall portions 17, 17, pivotally connected to the rear end of the side walls, as indicated at 18, 18. The arrangement is such that the pivoted wall portions normally form a closure for the rear end of the scraper, but are mounted to swing laterally and rearwardly into a position substantially parallel with each other, or into substantial alignment with the adjacent side walls of the scraper. The forward movement of the wall portions is limited by stops 19, 19, carried on forwardly projecting arms 20, 20, attached to the wall portions 17, said stops being adapted to engage the cross-member 15. The bottom margins of the rear wall portions 17, 17, are preferably inclined or turned inwardly to form cutting edges 21, 21, similar to the cutting edges 16, 16 of the side walls.

Means co-acting with the draft ropes are provided for actuating the rear wall portions, so as to open the rear end of the scraper

when it is being moved rearwardly, and to close the rear end while being moved forwardly. This is accomplished by operatively connecting both the head rope 10 and tail rope 11 to the pivoted end wall portions 17, 17, so as to tend to move them in opposite directions, depending upon the relative tension on the two draft devices. In the embodiment illustrated, the head rope 10 is provided with a pair of flexible terminals 23, 23. Each of said terminals is connected at its rear end to a clamp 24, or its equivalent, mounted on the cross-member 15. From thence it is trained rearwardly about a sheave 25 or its equivalent, mounted on a supporting member 26 extending inwardly from the end wall portion 17. From said sheave, the terminal 23 is trained forwardly through a guide 27, adjacent the front end of the side wall 13, and from thence it extends to the head rope 10, and is connected thereto by suitable means such as a clamp 28. A stop 29 is attached to the terminal 23 intermediate the guide 27 and clamp 28, and adapted to engage the guide 27, to limit the lateral swing of each wall portion 17 in a position substantially parallel with the opposite wall 17 as shown in dotted lines in Figure 1.

30 The tail rope 11 extends between the ends of the wall portions 17, 17, and is provided with a pair of terminals 30, 30, connected to arms 31, 31 extending inwardly from said wall portions as shown. It is obvious that the inwardly extending arms 31, 31 may be made integral with the supporting members 26, 26 if desired.

It will now be clear that my improved scraper above described, gathers its load at the toe of the pile while being moved rearwardly. The rear wall portions 17, 17 are opened laterally by the tail rope 11 into substantial parallel relation with each other, so as to offer a minimum resistance as the scraper cuts into the material. When the scraper has advanced sufficiently to gather its load, the pull on the tail rope 11 is discontinued, and tension is placed on the head rope 10. As the terminals of the head rope are connected to the lever arms 26, 26 on the rear wall portions 17, 17, a pull on the head rope tends to pivot the wall portions inwardly, to close the rear end of the scraper and move the material enclosed therein forwardly. Under some conditions, the rear wall portions may not become fully closed, but the material will be wedged between the wall portions sufficiently to move the load without losing an appreciable amount thereof.

In the preferred construction illustrated it will be seen that the head rope terminals 23, 23 are trained about pulleys 25, 25 to provide an increased leverage on the rear wall portions. It will further be observed

that the rear end of said head rope terminals are connected to the body of the scraper, and the side wall of the latter diverge slightly toward the front end, so that the scraper body will offer a considerable resistance against forward movement when material is in the scraper. By reason of this arrangement, a larger proportion of the pulling force is exerted toward closing the rear wall portions than would be the case if the scraper body offered less resistance against forward movement.

I claim as my invention:

1. A scraper having side walls, two end wall portions adapted normally to form a closure for one end of said scraper, and each pivotally mounted to swing about a vertical axis into position substantially parallel with the longitudinal axis of the scraper, draft means for reciprocably moving said scraper, and means co-acting with said draft means for actuating said pivoted wall portions.

2. A scraper having side walls, two end portions adapted normally to form a closure for one end of said scraper, draft means for reciprocably operating said scraper, and means operated by the tension on said draft means for moving said end portions into and out of substantial parallelism with each other.

3. A scraper having side walls, two end wall portions each pivotally mounted to swing laterally, draft means for reciprocably moving said scraper, and means co-acting with said draft means for actuating said pivoted wall portions.

4. A scraper having side walls, two end wall portions each pivotally mounted to swing laterally into substantial alignment with its adjacent side wall, draft means for reciprocably moving said scraper, and means co-acting with said draft means for actuating said pivoted wall portions.

5. A scraper having connected side walls, two end portions each pivotally connected with one of said walls to swing laterally, and two draft devices each having operative connection with said end portions and tending to move them in opposite directions.

6. A scraper having connected side walls, two end portions each pivotally connected with one of said walls to swing laterally, and two draft devices each having operative connection with said end portions and tending to move them in opposite directions, one of said draft devices having a pair of terminals, each connected to the scraper body and engaging a pulley mounted on one of said end portions.

7. A scraper having connected side walls, two end portions each pivotally connected with one of said walls to swing laterally, and two draft devices each having operative connection with said end portions and tending to move them in opposite directions,

one of said draft devices having a pair of terminals, each connected to the scraper body and engaging a pulley mounted on one of said end portions, the other of said draft devices having a pair of terminals each connected directly to one of said end portions.

8. A scraper having connected side walls, two end portions each pivotally connected with one of said walls to swing laterally, 10 two draft devices each having operative connection with said end portions and tending to move them in opposite directions, one of said draft devices having a pair of terminals, each connected to the scraper body 15 and engaging a pulley mounted on one of said end portions, and guide means for said terminals adjacent the front end of said scraper.

9. A scraper having connected side walls, 20 two closure members each pivotally connected with one of said walls to swing laterally, means extending inwardly from each of said members intermediate its ends, and two flexible draft devices for reciprocably 25 moving said scraper operatively connected with said inwardly extending means and tending to move their respective closure members in opposite directions.

10. A scraper having connected side walls, 30 two closure members each pivotally connected with one of said walls to swing laterally, means extending inwardly from each of said members intermediate its ends, and two flexible draft devices for reciprocably 35 moving said scraper one of said draft devices having flexible means connected with the side walls and movably engaging said inwardly extending means on said closure members.

11. A scraper having connected side walls, 40 two closure members each pivotally connected with one of said walls to swing laterally, means extending inwardly from each of said members intermediate its ends, and two flexible draft devices for reciprocably 45 moving said scraper one of said draft devices having flexible means connected with the side walls and movably engaging said inwardly extending means on said closure members, the other of said draft devices being directly connected to said inwardly extending means.

Signed at Chicago, Illinois, this thirteenth day of May 1921.

GLENN W. PACKER.
